S. C. WILSON

COMBINED RADIATOR AND HUMIDIFIER

Filed Dec. 10, 1923

Patented Dec. 8, 1925.

1,564,919

UNITED STATES PATENT OFFICE.

SAMUEL C. WILSON, OF CHICAGO, ILLINOIS.

COMBINED RADIATOR AND HUMIDIFIER.

Application filed December 10, 1923. Serial No. 679,648.

To all whom it may concern:

Be it known that I, SAMUEL C. WILSON, a citizen of the United States, and a resident of the city of Chicago, in the county 5 of Cook and State of Illinois, have invented certain new and useful Improvements in a Combined Radiator and Humidifier; and I hereby declare that the following is a full, clear, and exact description of the same, reference being had to the accompanying drawings, and to the numerals of reference marked thereon, which form a part of this specification.

This invention relates to humidifying devices for use in connection with radiators.

Heretofore it has been customary to place trays containing water upon radiators in order to humidify the atmosphere of the room in which they are placed. These trays, 20 however, have to be frequently replenished with water as the latter evaporates and further the amount of water vapor so supplied is relatively small as the tray and water therein do not receive any heat directly 25 from the steam in the radiator.

One of the objects of the present invention is to provide a humidifier which is fed with water or water vapor from the heating system.

30 Another object of the invention is to provide a humidifier which is fed with condensed water from the steam introduced into the radiator with which it is connected.

Other and further important objects of 35 this invention will be apparent from the disclosures in the specification and accompanying drawings.

This invention (in a preferred form) is 40 illustrated in the drawings and hereinafter more fully described.

On the drawings:

Figure 1 is a side elevation of a radiator fitted with a humidifier constructed in accordance with the present invention.

45 Figure 2 is a section on the line 2—2 of Figure 1.

Figure 3 is a section on the line 3—3 of Figure 2.

Figure 4 is a section on the line 4—4 of Figure 3.

50 Figure 5 is a section on the line 5—5 of Figure 3.

The invention is shown as applied to a steam radiator of usual construction composed of a series of units or coils 10 bolted together. Between two of these units is ar-

ranged a double unit 11 with a rectangular frame 12 formed integrally therewith and extending laterally therefrom. Fitting in a recess in the outer portion of this frame is 60 a plate 13 of porous material arranged between a pair of grids 14 and 15. Gaskets 16 of rubber or other suitable material provide a watertight connection and at the same time allow for differential expansion 65 of the plate 13 and the adjacent parts of the radiator.

The plate 13 may be made of a wide variety of porous materials such as wood, unglazed earthenware, felt or the like. The 70 plate 13 and the frame 12 enclose a chamber 17 wholly separated from the interior 18 of the steam coils formed integrally therewith except for conduits 19 and 20 leading to the bottom and top of the chamber 75 respectively.

Passage of fluid through conduit 19 is controlled by means of a valve 21 on the lower end of a spindle 22 passing through and in threaded engagement with a gland 23 in the upper part of the frame 12. In a similar manner passage of fluid through the conduit 20 is controlled by a valve 24 on a spindle 25 passing through and in threaded engagement with a gland 26. 85 Hand wheels 27 and 28 are provided for turning the spindles 22 and 25.

In operation the chamber 17 is preferably kept filled with water so that the latter is in contact with the porous plate 13 90 and can pass therethrough by capillary action and evaporate on the surface exposed to the atmosphere. For this purpose in operation the valve 21 is closed and the valve 24 opened so that steam can enter the chamber 17 and by condensation gradually fill the same up to the level of the conduit 20. The chamber may be drained at any time by opening the valve 21.

I am aware that many changes may be 100 made, and numerous details of construction may be varied through a wide range without departing from the principles of this invention, and I therefore do not purpose limiting the patent granted hereon, otherwise than necessitated by the prior art.

I claim as my invention:

1. A humidifying device comprising steam coils, a chamber formed integrally with said steam coils and having fluid connection with 110 the interior of said coils and a porous medium forming a part of one wall of said cham-

ber exposed to the atmosphere on one side and to fluids within said chamber on the other side.

2. A humidifying device comprising steam coils having a recess in one wall thereof and a porous medium covering said recess to form an enclosed chamber, said chamber having fluid connection with the interior of said coils.

10 3. A humidifying device comprising steam

coils having a vertically arranged recess in one wall thereof, a porous medium covering said recess to form an enclosed chamber, and valve controlled connections between the top and bottom of said chamber and the interior of said coils.

In testimony whereof I have hereunto subscribed my name.

SAMUEL C. WILSON.
